Inventor

UNITED STATES PATENT OFFICE.

HOWARD M. LEONARD, OF JACKSON, MICHIGAN, ASSIGNOR TO RUBY MANUFACTURING COMPANY, OF JACKSON, MICHIGAN.

ROOF STRUCTURE FOR PORTABLE BUILDINGS.

1,124,474.

Specification of Letters Patent.

Patented Jan. 12, 1915.

Application filed February 26, 1912. Serial No. 680,106.

To all whom it may concern:

Be it known that I, HOWARD M. LEONARD, a citizen of the United States, residing at the city of Jackson, county of Jackson, and 5 State of Michigan, have invented certain new and useful Improvements in Roof Structures for Portable Buildings, of which the following is a specification.

This invention relates to improvements 10 in roof structures for portable buildings.

The invention is especially adapted to roof structures for sheet metal portable buildings, of the knock-down variety.

The objects of the invention are, First, 15 to provide improved interchangeable roof sections and improved means for attaching the same. Second, to provide an improved construction of support for the roof sections. Third, to provide an improved ridge 20 construction. Fourth, to provide improved cornice construction. Fifth, to provide improved joint means between the roof sections.

Further objects and objects relating to 25 economies and details of construction will definitely appear from the detailed description to follow.

I accomplish the objects of my invention by the devices and means described in the 30 following specification.

The invention is clearly defined and pointed out in the claims.

A structure constituting a preferred embodiment of my invention is clearly illustrated in the accompanying drawing, forming 35 a part of this specification, in which:

Figure I is a perspective view of the framework for the roof structure. Fig. II is a perspective view in reduced form, of 40 the roof structure complete. Fig. III is an enlarged detail view, partially in section, on line 3—3 of Fig. II, showing details of the connection of the roof with the side wall and the cornice structure. Fig. IV is an

45 enlarged detail in sectional plan, on line corresponding to line 4—4 of Fig. III, showing the corner construction and the connection and relation of the parts. Fig. V is a detail perspective view of one of the corner clip plates. Fig. VI is an enlarged detail sectional view on line corresponding to line 50 6—6 of Fig. II, showing the joints between the roof sections. Fig. VII is an enlarged

detail sectional view on line corresponding to line 7—7 of Fig. II, showing the peak or ridge structure. Fig. VIII is an enlarged detail sectional view on a line corresponding to line 8—8 of Fig. II, showing details of the cornice structure at that point. Fig. IX is an enlarged detail perspective view of the peak or terminal of the roof. Fig. X is an enlarged detail sectional view on line corresponding to line 10—10 of Fig. IX, showing details of construction of the peak ornament or terminal at that point. Fig. 60 XI is an enlarged detail vertical sectional view through the roof terminal and ridge structure, taken on a line corresponding to line 11—11 of Fig. XII. Fig. XII is a detail transverse sectional view through the 70 ridge taken on a line corresponding to line 12—12 of Fig. XI. Fig. XIII is a detail cross sectional view, taken on a line corresponding to line 6—6 of Figs. II and III, of a modified structure of roof joint. 75

In the drawing similar numerals of reference refer to similar parts throughout the several views, and the sectional views are taken looking in the direction of the little arrows at the ends of the section lines. 80

Considering the numerals of reference, my improved roof structure is supported on corner posts 1—1 and the intermediate posts 2. These parts are connected together by the stringers 3 having lugs 3' for receiving 85 and retaining the side wall structures.

The pairs of rafters 4 are joined at their upper ends by plates 5, suitably riveted or bolted thereto. The rafters are made of angle bar which is notched at 6 and folded 90 downwardly and secured to the posts 1 and 2 by suitable bolts 7, as clearly appears in detail in Figs. III and IV. Corner clip plates 9 are interposed between the various parts to retain them securely in position 95 and in alinement.

Side walls made up of plates 10, supported by suitable angle bar frame 12, over which the plates are folded, are provided with upwardly-projecting tongues 13 in 100 proximity to the frame, forming a groove to receive appropriate tongue members on the roof sections. Purlin plates 14 made up of L-shaped angle bars secured to the rafters by one limb, the other limb projecting upwardly at right angles to the rafter, are 105

provided with downwardly-projecting retaining lugs 15 on their upper edges, as clearly appears in Figs. I and III.

The roof is made up of identical sections 17, with the exceptions that those at the gable ends are somewhat different in form, as will be explained, to produce a cornice effect. These roof sections are supported by frames made up of L-shaped angle bars 18 disposed to form a suitable frame-like support for each section, one limb projecting out at the edges and the other forming a frame-like rib at the back. The roof plates are secured to these angle bars by rivets 19, or by spot welding. The lower edge or eaves of each roof section is folded back upon itself at 20, as indicated.

A tongue piece 20' is secured within the angle of the frame at this point and projects downwardly into the groove between the flange 12 and the tongue 13, already described, at the upper edge of the side wall section, clearly detailed in Fig. III.

The roof plates are secured to these angle bar frames 18 and the sides of the same are turned upwardly at 21 at the meeting edges between the roof sections, and the outer edge is turned up at 34 to give a cornice effect. Over these up-turned meeting edges, an inverted U-shaped strip 22 is fitted and crowded down over the same and is retained in position by the fastening 23 like a McGill paper fastener, inserted up through the same between the frame bars 18 and the upturned edges 21 and expanded out over the top of the retaining strip 22, as illustrated specifically in Figs. VI and VII. This makes a very secure roof coupling and one which can be very readily removed. It is a very easy matter to supply new fastening devices in the event that they become broken or lost.

A ridge piece 24 is provided, folded to suitable ornamental form, each side 25 of which is extended downwardly at the proper angle and folded back upon itself, thence downwardly at 26 and thence downwardly and outwardly at 27 forming grooves or channels into which the upper ends of the roof sections 17 fit and are disposed, forming a very secure and satisfactory joint at that point, which is thoroughly weather proof.

An end ornament or roof terminal 28 of any suitable form is provided with sleeve 29 to fit over the ridge piece 24 at each end and conform thereto. Each ornament is provided with downwardly-extended flanges 30 which close under the projection end 60 cornice forming a secure weatherproof joint at that point and securing a very ornamental effect. This piece can be formed of a single piece of metal by the use of an appropriate pattern.

65 The manner in which the end cornice is

formed appears clearly from Figs. VIII, IX, X and XI, where the outer edge of the roof section is folded upwardly at 34 and downwardly and back to the frame 18 at 32. A cornice piece embraces the same at 34 and 70 extends under at 35 with a downwardly-projecting flange 37 to engage in suitable grooves on the upper ends of the end panels of plates of the building.

The end of the building is supported by 75 suitable door posts 38 and is provided with a cross bar 39 at the top. A collar beam 40 is above the cross bar 39 and cross bars 41 extend between posts 1 and 38. An attaching plate 42 is provided in the gable. 80 Diagonal brace rods 43 extend from corner to corner of the frame.

In Fig. XIII, I show a modification of the roof joint, in which a special joint strip is dispensed with and the upturned flanges are 85 conformed to engage the one over the other. The left-hand flange 44, for instance, being formed by a recurved edge of the sheet metal plate of the roof section, and the right-hand upturned edge flange 45 of the 90 adjacent section being folded into a grooved flange to fit over the same. This distinctly appears in Fig. XIII where the left-hand member 44 is shown fitting into the grooved right-hand member 45 of the adjacent section. This structure is more permanent than that of the preferred form, but is capable of separation by opening the grooved member 45 and lifting the sections apart when they have been moved along the 100 purlin plates out of engagement with the lugs.

Having thus described my improved roof structure, I desire to state that I have shown it in detail in the preferred form. It is 105 capable of considerable modification without departing from my invention which is clearly defined in the appended claims.

Having thus described my invention, what I claim as new and desire to secure by Letters Patent is:

1. In a roof structure, the combination of suitable rafters; purlin plates of angle bar with upwardly-projecting ribs secured thereto and with laterally-projecting lugs 115 on said ribs; roof sections made up of sheet metal; a frame formed of angle bars for each of said roof sections, one limb of said angle bars forming downwardly-projecting ribs on the under side thereof, the said projecting ribs of each frame being provided with L-shaped slots to receive the edge and lugs of the upwardly-projecting ribs of said purlin plates to retain the said sections in place, all coacting substantially as described 120 and for the purpose specified.

2. In a roof structure, the combination of suitable rafters, sheet metal roof sections detachably carried thereby, a detachable ridge structure of sheet metal folded upon itself 130

to form channels at each side for receiving the upper ends of the roof sections, and suitable detachable terminals conformed to the ridge structure and fitting over the ridge structure and roof sections and having portions engaging underneath the roof sections, as described.

3. In a roof structure, the combination of suitable rafters, detachable sheet metal roof sections carried thereby, downwardly-projecting sheet metal tongues on said roof

sections in line with the side walls, and side walls with groove structures to receive said tongues, as described.

In witness whereof, I have hereunto set my hand and seal in the presence of two witnesses.

HOWARD M. LEONARD. [L. S.]
